UNITED STATES PATENT OFFICE.

EDWIN BALL STIMPSON, OF BROOKLYN, NEW YORK.

ENVELOP-FASTENER.

No. 808,489.

Specification of Letters Patent.

Patented Dec. 26, 1905.

Application filed July 18, 1904. Serial No. 217,037.

To all whom it may concern

Be it known that I, EDWIN BALL STIMPSON, a citizen of the United States, residing in the borough of Brooklyn, in the county of Kings, 5 in the city and State of New York, have invented certain new and useful Improvements in Envelop-Fasteners, of which the following is a specification.

This invention relates to the class of fastening devices ordinarily made from sheet metal and employed for securing the flaps of envelopes and for similar purposes and uses; and the object of the invention is to provide 10 a fastener having an extended and firm base with the maximum space between the securing-clips and at the same time to avoid waste material in cutting the fasteners from the sheet metal. In this construction all of the metal employed may go into the fastener and 15 is utilized.

In the accompanying drawings, which illustrate an embodiment of the invention in its preferred form, Figure 1 is a perspective view of the fastener in its finished shape with the 20 two long prongs bent into their upright position. Fig. 2 shows the fastener secured by its clips to the body of an envelop. Fig. 3 shows the fastener in its flat form before the clips are formed on it. Fig. 4 illustrates the 25 mode of cutting the fasteners from a strip of sheet metal without waste. Fig. 5 is a view, on a larger scale than Fig. 4, illustrating the swaging of the clips before cutting the fasteners from the strip.

30 In its flat form, as seen in Fig. 3, the fastener has the form of a lozenge, with the prongs cut or punched from the same. 1 designates the body, and 2 the prongs. Fig. 1 shows these prongs bent upright, so as to stand side by side near the middle of the base, as they 35 must to pass through hole or eyelet in the flap of the envelop. The securing-clips 3 are formed by bending back angles or corners of the lozenge or quadrilateral to about a right 40 angle to the face thereof. All four of the corners may be so bent back, as seen in Fig. 1.

Fig. 2 shows one application of the fastener. In this view E designates the body of an envelop or paper mailing-bag, and F the 45 flap of the same, having in it the usual eyelet or reinforced hole h. The clips of the fastener, which are passed through the ply of the envelop and clenched on the inside thereof, are indicated in this view by dotted lines.

50 Fig. 4, which is a somewhat diagrammatic and illustrative view, shows how the lozenge-

shaped fasteners are cut, along oblique lines y, from a strip S of metal without waste of the material, the prongs 2 being punched from the body 1 by a die. The two fasteners 60 at the right in this figure are shown as detached and that one at the extreme right has its angles bent back to form the securing-clips.

It is desirable to have the securing-clips 65 swaged to a rather thin edge at the point where they pass through the paper, and this may be done with dies while the clips are still in the strip. This is illustrated in the somewhat diagrammatic view Fig. 5. In this 70 view the clips are line-shaded at z to indicate the swaging to thin them at the points.

It will be noted that this construction of the fastener avoids all waste of stock; that it avoids excessive wear of the dies by reason of 75 the small proportion of punching-out and cutting required from the dies; that it provides an extended base with widely-separated points of attachment to the envelop, a matter of great importance where the paper of 80 the envelop is inferior, and that it puts all the metal of the stock used into the fastener.

Of course the form of the quadrilateral may be varied somewhat without departing from the invention; but for general use the 85 lozenge form shown is that preferred.

The length of the prongs 2 is not material to the invention. They may extend entirely out to the angle of the quadrilateral.

Having thus described my invention, I 90 claim—

1. A fastener, having a primarily quadrilateral body with portions at a plurality of the angles thereof bent back to form securing-clips, and a prong or prongs punched from 95 the body.

2. A fastener, having a primarily quadrilateral lozenge-shaped body with portions at a plurality of the angles thereof bent back to form securing-clips, and its prongs punched from 100 the body.

3. A fastener, having a primarily quadrilateral body with portions at a plurality of its angles bent back and swaged to form sharp securing-clips, and having its prongs punched 105 from the body.

4. A fastener of sheet metal, having a primarily lozenge-shaped body with prongs 2 punched out therefrom, and having securing-prongs 3 formed by bending back its angles 110 or corners to a position substantially at right angles to its face.

2

5. A fastener, having a primarily quadrilateral body with portions at a plurality of the angles thereof bent back to form securing-clips, and a prong or prongs punched from the body and projecting therefrom in a direction opposite to that in which the securing-clips project.

6. An envelop-fastener of sheet metal, having a primarily quadrilateral form with portions at its angles bent back to form securing-clips, and prongs punched from the body and

bent outward from the face of the same in a direction opposite to that in which the clips project, said prongs being face to face and connected to the base at points near together. ¹⁵

In witness whereof I have hereunto signed my name, this 14th day of July, 1904, in the presence of two subscribing witnesses.

EDWIN BALL STIMPSON.
